SEWING CABINET

A. Ivar Ekstrom, Rockford, Ill.

Application September 1, 1938, Serial No. 227,889

5 Claims. (Cl. 242—137)

This invention relates to a new and improved sewing cabinet.

The principal object of my invention is to provide a sewing cabinet providing ample storage space for thread, buttons, needles, etc., within a comparatively compact cabinet, the arrangement being such that the user can get at any of the materials quickly and easily.

A salient feature of the cabinet of my invention is the provision of a rotary rack demountably supported in the cabinet and having a plurality of spindles thereon adapted to receive spools of thread or yarn, the rack being rotatable about a horizontal axis so as to bring any selected spindle quickly into position at the open front of the cabinet, so that the operator can remove thread from a spool or take a spool off or put a spool on the spindle. A special feature in this connection is the mounting of the rack so that the ends of the spindles are disposed normally in closely spaced relation to a partition wall in the cabinet to keep the spools in place thereon, there being one point at which spools may be placed on or removed from the spindles through a cut-out portion of the partition wall. Still another feature in this connection is the provision of spring means for holding the rack against displacement from operative position in the cabinet, said means serving also to exert a frictional drag upon the rotation of the rack, although permitting the rack to be turned easily from one selected position to another.

Another important feature of my invention is the provision of pivoted trays disposed in superimposed relation in a compartment in the cabinet having a single elongated pivot screw passing through the two trays and into a supporting leg on the cabinet, the two trays having the outer ends thereof cut on an arc with the screw as a center so as to permit swinging the trays into and out of a rectangular space in the cabinet.

Another important feature of my invention is the provision of an improved thread cutter in the form of a blade pressed into the soft wood of a partition wall adjacent the spool supporting rack, so that the user can quickly cut off any desired length of thread or yarn, without the use of scissors.

The invention is illustrated in the accompanying drawing, in which—

Fig. 1 is a perspective view of a sewing cabinet made in accordance with my invention, showing the door thereof opened so as to reveal the spool supporting rack and the swingable trays thereon, as well as the novel thread cutter, one

of the trays being indicated in dotted lines in an opened position, and

Figs. 2 and 3 are sections taken approximately on the lines 2—2 and 3—3 of Fig. 1, looking in the direction of the arrows, the door being shown closed in Fig. 3.

The same reference numerals are applied to corresponding parts throughout the views.

The cabinet 5 has a door 6 on the front thereof hinged as at 7 to swing downwardly in opening, a support 8 being preferably provided to limit the opening movement of the door and support it in a substantially horizontal position. A vertical partition wall 9 extends from the open front of the cabinet back to a longitudinal partition wall 10 disposed in spaced parallel relation to the rear wall 11 of the cabinet. The rear compartment 12 thus provided has a separate smaller door 13 hinged as at 14 to swing downwardly in opening, so that a convenient place is provided for storing work and materials. Additional storage space is provided in the open front section to the right of the partition wall 9, where, as indicated, a vertical partition wall 15 is provided together with a shelf 16, affording spaces to store various sized articles handily. Short legs 17 project downwardly from the four corners of the cabinet for support thereof in elevated relation to the top of the table or other support on which the cabinet may be placed. A handle 18 at the center of the top of the cabinet permits one to lift the cabinet and carry it from one place to another readily. It will be understood that when the doors 6 and 13 are closed, suitable catches, such as the one shown at 19, will serve to lock the same releasably in closed position, so that there will be no danger of either of the doors opening accidentally.

In accordance with one of the principal objects of my invention, I provide a rack 20 demountably and rotatably supported in the compartment to the left of the partition wall 9, adapted to support a full set of spools of thread, including all that a housewife is ordinarily accustomed to keep on hand, or more. The rack 20 comprises a central mandrel 21 carrying a disk 22 near one end thereof that is equipped with a plurality of spindles 23 in circumferentially spaced relation near the periphery thereof and substantially parallel with the mandrel 21. The spindles are of a size adapted to be slipped easily through the center holes in the spools, and each spindle is adapted to support six or more spools thereon. The rack herein disclosed has seven spindles thereon, so that there is ample storage space

in the present cabinet for whatever thread a housewife is apt to use. Two hangers 24 and 25 are provided adjacent opposite ends of the rack 20, one on the inner side of the end wall of the cabinet and the other on the partition wall 9, and these provide semi-circular bearings 26 and 27 into which the opposite ends of the mandrel 21 are adapted to be entered for rotary support of the rack. A leaf spring 28 carried on the top 10 wall of the cabinet rides on the periphery of the disk 22, as clearly appears in Fig. 2, and serves to keep the mandrel 21 properly engaged in the bearings 26 and 27, while at the same time acting as a frictional shoe to resist turning of the 15 rack. The resistance to turning is just enough to hold the rack in an adjusted position, but not enough to interfere with the easy turning of the rack from one position to another. The spring pressure is also light enough so that one can 20 without difficulty remove and replace the rack, as, for example, when the spools are to be placed thereon or if a number of spools are to be removed at a time and others substituted. The cabinet is so designed, as I will now describe, to 25 enable one to remove or replace a single spool conveniently without removing the rack.

It will be noticed that the partition wall 9 has a substantially semi-circular cut-out portion 29, so located with respect to the bearings 26 and 27 30 and the rack 20 that any one of the spindles 23 carrying the spools, like that shown at s in Fig. 3, is adapted to be brought into register with substantially the center of this cut-out portion, to 35 permit slipping a spool off the end of the spindle and replacing the same. The spindles 23 terminate in such closely spaced relation to the partition wall 9 that the spools will not slip off the ends thereof at any other part in the rotation of the rack. The hanger 25, it will be noticed, is 40 made small enough to lie wholly inside the circle of spools on the spindles 23, so that there will be no interference with the rotation of the rack.

There is another small cut-out portion 30 on the front edge of the partition 9 above the cut-out portion 29, and a third cutter blade 31 is driven into the soft wood of the partition wall 9 leaving its sharp edge exposed in the cut-out portion 30. This blade makes it very convenient for the housewife to pull out the desired length of thread 45 off a spool and cut it without having to look around for and pick up scissors to do the job. The proximity of the thread cutter to the rack of spools is obviously of advantage because there will be only a short loose end left after cutting the thread, which can be readily wound back 50 upon the spool.

Two trays 32 and 33 having pockets provided therein for the convenient storage of buttons, needles, and other small articles generally kept in 55 sewing cabinets, are mounted in superimposed relation in the compartment to the left of the partition wall 9 under the rack 20 and are swingable outwardly from said compartment on the screw 34 as an axis. This screw is clearly illustrated in Fig. 2. It has an elongated smooth shank which has a working fit in holes 35 and 36 in the trays 32 and 33, respectively, and its threaded end extends down into the leg 17 therebeneath, whereby to provide the desired rigidity 60 for the screw 34 and avoid likelihood of its becoming wobbly in service. The upper tray 32 is cut away on the outside, as at 37, and the lower tray 33 is cut away on the inside, as at 38, to provide a finger-tip grip 39 permitting one to swing out 65 the lower tray 33 without disturbing the upper 70 tray.

The lower tray is shown swung out in Fig. 1 in dotted lines, revealing the arcuate form of the end 40 remote from the screw 34. Both trays have their ends struck on arcs with the screw 34 as a center so as to permit swinging 75 the trays with respect to the partition wall 9.

In passing, attention is called to the tapered plug 41, elongated strip 42, strap 43, and nail 44 provided on the inside of the door 6. The plug 41 and strip 42 are of cork or other suitable material, the plug forming a convenient support for a thimble and the strip providing a convenient pin cushion, which in the closed position of the door, as clearly appears in Fig. 3, occupies a position in the cut-out portion 29, so that there is 15 no interference with the closing of the door 6. A pair of scissors may be suspended on the nail 44 and engaged in the strap 43.

It should be clear from the foregoing description that I have provided a sewing cabinet combining many handy features. The housewife finds in this cabinet a place for everything and the things can be stored so that there is no danger of their becoming disarranged. Spools of thread can be placed on the rack in whatever arrangement the housewife prefers, and she never has any difficulty in finding a particular spool when she wants some special thread for a given job. She can readily draw out the amount of thread wanted and can cut it off quickly and re-wind 30 the loose end on the spool. Then, too, an empty spool can be removed quickly and replaced with a fresh one without disturbing the rest of the spools.

The present cabinet is moreover of light weight 35 and economical construction, and despite its small size provides adequate storage space for such odds and ends of sewing material which the average housewife expects to keep in a sewing cabinet.

The foregoing description conveys a good understanding of the objects and advantages of my invention. The appended claims have been drawn with a view to covering all legitimate modifications and adaptations.

I claim:

1. In a sewing cabinet having a vertical partition wall therein in spaced parallel relation to another wall, and a closure for said cabinet adapted to lie in close proximity to the outer edges 50 of said walls, a rotatable spool carrier mounted between said walls for rotation on a horizontal axis, and horizontal spool spindles in spaced relation on said carrier having free ends lying in closely spaced relation to said partition wall, the 55 latter having an outer edge portion cut away in substantially concentric relation to the end of a spindle of said carrier, substantially as and for the purpose described.

2. In a sewing cabinet having a wall therein 60 in spaced parallel relation to another wall, a spool carrier comprising a mandrel, a disk concentrically mounted on one end portion thereof, and a plurality of spool supporting spindles projecting from the disk in circumferentially spaced relation and substantially parallel to the mandrel, a pair of concentric substantially semi-circular bearings on said walls adapted detachably to receive the ends of said mandrel for rotary support of the spool carrier in the cabinet, and a leaf spring supported in spaced relation to one of said bearings and arranged to frictionally engage the periphery of said disk to hold the carrier mandrel yieldingly in assembled position 75.

in said bearings while resisting rotation of said carrier.

3. In a sewing cabinet having a wall therein in spaced parallel relation to another wall, a spool carrier comprising a mandrel, a disk concentrically mounted on one end portion thereof, and a plurality of spool supporting spindles projecting from the disk in circumferentially spaced relation and substantially parallel to the mandrel, a pair of concentric bearings on said walls to receive the ends of said mandrel for rotary support of the spool carrier in the cabinet, and a leaf spring supported in spaced relation to one of said bearings and arranged to frictionally engage the periphery of said disk to resist rotation of said carrier.

4. In a sewing cabinet, the combination of a pair of spaced parallel walls, and a closure movable to and from a position close to the outer edges of said walls, a spool carrier rotatably mounted between said walls having circumferentially spaced spool supporting spindles thereon on which spools are adapted to be slidably supported by entry of the spindles through cen-

ter holes in the spools, said spindles terminating in closely spaced relation to one of said walls, and said wall having a semi-circular notch in the edge thereof to permit removal of spools from and placing of spools on the spindles by passage through the notch when a spindle is in register therewith, and said closure having means providing a projection on the inner side thereof which in the closed position of said closure projects into said notch.

5. In a sewing cabinet having spaced parallel vertical walls, a support pivoted for movement between said walls and carrying a plurality of horizontal spindles in substantially parallel relation adapted to receive spools by entry through the center holes therein, the spindles being in spaced relation to the pivotal axis, one of said walls serving to block the removal or displacement of spools from the ends of the spindles until the spindles are moved by movement of the support to a forward position relative to the wall last named, so that the spools may be moved off the spindles past the front edge of said wall.
